UNITED STATES PATENT OFFICE.

JOHN B. VAN HOUTEN, OF NEWARK, NEW JERSEY.

DESIGN FOR AN EAR-RING PENDANT.

SPECIFICATION forming part of Design No. 14,853, dated March 4, 1884.

Application filed November 21, 1883. Term of patent 7 years.

In all whom it may concern:

Be it known that I, JOHN B. VAN HOUTEN, a citizen of the United States, residing at Newark, in the county of Essex and State of New Jersey, have invented and produced a certain new and original Design for Ear-Ring Pendants; and I do hereby declare the following to be a full, clear, and exact description of the invention, such as will enable others skilled 5 in the art to which it appertains to make and use the same, reference being had to the accompanying drawings, and to letters of reference marked thereon, which form a part of this specification.

10 In said drawings, Figure 1 is a front view, and Fig. 2 a side view, these figures being deemed sufficient to fully illustrate the design.

The leading feature of the design consists in 15 the configuration of the pendant portion of the ear-ring substantially as will be hereinafter described.

In the drawings, A represents an ear-plate, or plate to which the ear-wire is attached; and

B, a pendant suspended from said plate, to 25 which pendant the design more especially relates. Said pendant, when viewed from the front, as in Fig. 1, is approximately triangular, or broadens toward its base, as at b, the front surface of said triangular portion being 30 rounded, as at c. Across the upper portion of the pendant the same projects, substantially as shown, the projecting portion being band-shaped, as at d. The front longitudinal center portion of the pendant projects more prominently forward, and is also triangular or broadened toward the base. 35

What I claim as my design is—

The design for a pendant of an ear-ring, substantially as shown and described. 40

In testimony that I claim the foregoing I have herenunto set my hand this 16th day of November, 1883.

JOHN B. VAN HOUTEN.
